UNITED STATES PATENT OFFICE.

CHARLES B. ANDREWS, OF HIGH BRIDGE, NEW JERSEY, ASSIGNOR TO TAYLOR-WHARTON IRON AND STEEL COMPANY, OF HIGH BRIDGE, NEW JERSEY, A CORPORATION OF NEW JERSEY.

DREDGE-TUMBLER.

1,333,367.

Specification of Letters Patent.

Patented Mar. 9, 1920.

Application filed March 6, 1919. Serial No. 280,926.

To all whom it may concern:

Be it known that I, CHARLES B. ANDREWS, a citizen of the United States, residing at High Bridge, in the county of Hunterdon 5 and State of New Jersey, have invented certain new and useful Improvements in Dredge-Tumblers, of which the following is a specification.

Dredge tumblers, for some years past, 10 have been constructed largely of manganese steel, because of its enormous strength and wear-resisting properties, qualifications very desirable in dredge-work.

Contemplating the use of this material, 15 but not necessarily restricted thereto, and having in mind the difficulty and exacting requirements of its casting and subsequent heat-treatment, one of the principal objects of this invention is to provide a tumbler 20 possessed of great strength and constructed on the unit plan in order to minimize loss in the foundry and in order to facilitate the renewal or replacement of worn or damaged parts. Another principal object is to 25 provide a three-piece tumbler, comprising a flanged or spool member and a pair of opposed drum or hub members introduced endwise of the spool member, the spool and drum members being interfitted and held 30 against relative movement in a novel manner as will be enlarged upon hereinafter. Another principal object is to provide, in a tumbler of the character stated, a portable drum or carrier formed of mated sections 35 having a metallic bond or interlock. Another principal object is to provide a tumbler spool having a reversely tapered bore and mated spool-carrying elements having a wedge fit therewith. 40 With the foregoing and other objects in view, the nature, characteristic features and scope of the invention will more readily be understood from the following description taken in connection with the accompanying drawing, forming a part hereof, 45 wherein—

Figure 1 is a view principally in longitudinal section of a tumbler embodying features of my invention.

Fig. 2 is a longitudinal sectional view of the drum sections and their connecting links in detached relation.

Fig. 3 is a fragmentary transverse sectional view of the tumbler.

Fig. 4 is a fragmentary longitudinal section of a modification. 55

Referring to the drawing, the numeral 5 designates the spool, which, as to its outer peripheral wall and flanges, may be as usual. Its inner peripheral wall is formed on opposed tapering lines, indicated at 6, 6, in order to establish a ground joint between it and the tapered walls of the carrier. Otherwise stated, the spool has a reversely tapered bore and the spool-carrying elements, hub or drum sections, are designed 60 to be wedged therein.

The spool carrier is formed of two opposed coincident or mated drum sections 7, 7, which, as indicated in Fig. 1, are confronted by introducing them endwise of the spool. Each drum section 7 is a single casting with a tapered external peripheral wall 8, inner peripheral wall or hub 9, solid end wall 10, and integral webs or strengthening 70 ribs 11. The webs 11 have offset provisions, lugs or keys 12, and when the sections are pressed together and the parts are juxtaposed, the web extensions 12 are bridged and metallically bonded by carbon steel links 75 13, or their equivalents, by, for example, shrinking said links to place in a manner well understood.

The wedge fit and ground joint between the spool and mated spool-carrying sections 85 is ordinarily sufficient to prevent relative rotative movement, but as a further factor of safety I provide the inner wall of the spool with a lug 14 and the drum sections with corresponding slots or recesses 15. 90

The mated drum or hub sections 7 may have the usual soft metal lined keyways 16, 17.

For comparatively small size tumblers the bore of which is too small to conveniently 95 admit of introducing the links 13, I may employ in lieu of the links the through bolts 18, Fig. 4, or their equivalent, the tumbler faces having countersunk provisions 19, 20, to accommodate the bolt heads and nuts. 100

Evidently, I have provided a tumbler of simple yet rugged construction, the elements whereof are readily separable for major or minor repairs. The provision of the mated drum sections minimizes faulty castings and 105 works an economy in maintenance and repairs in that damage to one member can be rectified without disturbing the relation be-

tween the other section and the spool, and in the event of damage to the spool necessitating its replacement, it is a very simple matter to dissolve the bond between the 5 mated sections or to disconnect the substitute fastenings and to unwedge said sections with respect to the spool.

While the spool and drum elements will generally be made of manganese steel, I may 10 depart therefrom if the occasion warrants. For example, I may construct the spool or flange member of manganese steel and the drum elements of carbon steel.

I claim:

- 15 1. A dredge tumbler, comprising a spool, a sectional carrier formed of mated drum sections with confronting radial offset portions, and means uniting said offset portions.
- 20 2. A dredge tumbler, comprising a spool, a sectional carrier formed of mated drum sections with confronting webs having radially disposed lugs or offsets, and interlocking means for the lugs.
- 25 3. A dredge tumbler, comprising a spool and mated drum sections on which it is fixedly mounted, said drum sections having solid end walls, hub members and confronting radial offset portions, and a metallic bond connecting said offset portions.

4. A dredge tumbler, comprising a spool, 30 a sectional carrier formed of mated drum sections with webs, and coupling members bridging and shrunk upon the webs.

5. A dredge tumbler, comprising a spool, 35 a sectional carrier formed of mated drum sections whereof each has a ground fit with the spool, and links bridging and shrunk upon the drum sections.

6. A dredge tumbler, comprising a spool 40 consisting of a single casting having a reversely tapered bore, a sectional carrier formed of mated drum sections whereof each has a ground fit with the spool, and links bridging and shrunk upon the drum sections.

7. A dredge tumbler, comprising mated 45 drum sections having tapered rims and hub members connected by solid end walls and webs, a spool member consisting of a manganese steel casting having a reversely tapered bore which effects a ground or wedge fit with said tapered rims, coupling means for the drum sections, and supplemental means to prevent relative rotation of the parts.

In testimony whereof I affix my signature.

CHARLES B. ANDREWS.
